UNITED STATES PATENT OFFICE.

ADOLPH LYON, OF DETROIT, MICHIGAN.

CARPET-BEATER.

SPECIFICATION forming part of Letters Patent No. 361,638, dated April 19, 1887.

Application filed May 10, 1886. Serial No. 201,644. (No model.)

To all whom it may concern:

Be it known that I, ADOLPH LYON, of Detroit, in the county of Wayne and State of Michigan, have invented new and useful Improvements in Carpet-Beaters; and I do hereby declare that the following is a full, clear, and exact description thereof, reference being had to the accompanying drawings, which form a part of this specification.

10 This invention relates to certain new and useful improvements in many-sided rotary carpet-beaters; and the invention consists in the peculiar combinations and the novel construction, arrangement, and adaptation of 15 parts, all as more fully hereinafter described and claimed.

Figure 1 is an end elevation of my improved carpet-beating device. Fig. 2 is a perspective view of the same.

20 In the drawings, A represents one of the heads of my carpet-beating wheel, there being two such heads—one at each end—exactly alike in size and form, and each centrally supported upon a stub-shaft, a, adapted to run in suitable

25 stationary bearings, (not shown,) and provided with any of the known appliances for giving the device a rotary motion. These ends are of a very irregular stelliform shape, and they are connected together by means of slats

30 B, secured to longitudinal bars fastened to the heads in such a manner as to leave spaces between the slats for the escape of the dirt. One of the sides, as C, is fitted to act as a door, through which the carpets to be operated upon 35 are put into the wheel. The portion d of one side is the equal in length of the portion e of the opposite side, while portion f is equal to portion g, portion h is equal to portion i, and portion k is equal to portion l, so as to destroy

40 any regularity, and these sides or portions of sides are so arranged that a narrower portion

is opposite a wider portion on the opposite side. By this construction there are provided two kinds of pockets, the smaller being the carrying-pockets and the larger being the 45 pockets into which the carpets successively fall. This peculiar construction prevents, in the rotation of the wheel carrying several carpets under action, such carpets from falling upon each other as they fall from a higher 50 pocket to a lower one, so that each successive carpet falls upon the non-yielding slats, and by such impact are deprived of their dust.

I attach importance to the form of my wheel and to the fact that the narrow side or portion 55 f on one side be opposite the wider portion e of the opposite side and the narrow portion g, adjacent to the portion e, be opposite the wider portion d on the opposite side adjacent to the portion f, for by this arrangement I get the 60 maximum distance for the carpets to fall, whereby they are more thoroughly cleaned. The large pockets m n and the small pockets o p are diametrically opposite each other, as shown. 65

What I claim as my invention is—

1. A rotary carpet-cleaning machine consisting of a wheel of irregular outline having a narrower portion on one side opposite a wider portion on the opposite side, substantially as 70 and for the purpose specified.

2. The rotary carpet-cleaning machine described, consisting of the heads A, of irregular shape, as shown, with the narrow portion on one side opposite the wider portion on the opposite side, longitudinal bars secured to said heads, and the transverse slats B, secured to said bars, substantially as described. 75

ADOLPH LYON.
